UNITED STATES PATENT OFFICE.

EDWARD A. ARCOUET, OF CHICAGO, ILLINOIS.

SAND-BLAST APPARATUS.

No. 845,919.

Specification of Letters Patent.

Patented March 5, 1907.

Application filed March 22, 1906. Serial No. 307,337.

To all whom it may concern:

Be it known that I, EDWARD A. ARCOUET, a citizen of the United States, residing at Chicago, in the county of Cook and State of Illinois, have invented certain new and useful Improvements in Sand-Blast Machines, of which the following is a full, clear, and exact specification.

This invention relates to improvements in sand-blast machines particularly adapted for abrading purposes or for cutting letters, designs, &c., upon glass or other surfaces; and the object of the same is to construct an improved device of this character from which a stream of sand may be conveyed through a pipe and directed with great force against the surface to be operated.

A further object is to construct an improved device of this character in which pressure exerted upon a body of sand or similar abrading material contained within a receptacle will convey the material through a pipe and discharge the same through a nozzle against the surface to be acted upon and by means of which nozzle the material may be easily directed.

A further object is to construct an improved portable device of this character for utilizing compressed air which is directed into a tank containing an abrading material, for discharging the same therefrom, and also to provide improved means for regulating the discharge of the material.

A further object is to construct an improved portable device of this character which will be light in weight, simple and durable in construction, cheap to manufacture, and efficient in operation.

To the attainment of these ends and the accomplishment of other new and useful objects, as will appear, the invention consists in the features of novelty in the construction, combination, and arrangement of the several parts hereinafter more fully described and claimed, and shown in the accompanying drawing, illustrating an exemplification of the invention, and in which—

Figure 1 is a vertical section of a machine constructed in accordance with the principles of this invention. Fig. 2 is a sectional view on line 2-2 of Fig. 1. Fig. 3 is an enlarged detail sectional view of the regulating valve. Fig. 4 is a detail view of the locking means for holding and securing the valve in the desired position.

Referring more particularly to the draw-

ings, the numeral 10 designates a closed tank constructed of any suitable material and of any desired size and configuration. A suitable threaded opening may be provided in the top of the tank, which is adapted to be closed by a plug or cap 11, and through said opening the sand or abrading material is adapted to be inserted into the tank.

The bottom is preferably convexed and is provided with a centrally-disposed opening, to which is secured one end of a tube or pipe 12. The tank is also provided with an opening 13 in its wall, which is located, preferably, adjacent the bottom.

The support 14, constructed of any suitable material, is provided for the tank and is preferably in the form of an open cylinder or ring and secured adjacent the top and on the inside thereof on brackets or lugs 15. This support is of the same shape as the tank and of a slightly larger diameter, so that the lower extremity of the tank may enter therein and rest upon the brackets or lugs 15, any number of which latter may be provided suitable for the purpose.

Secured to the free extremity of the pipe or tube 12, which depends from the bottom of the tank 10 and in any suitable manner, such as by screw-threads, is a coupling 16, which is provided with an opening 17, extending through the bottom thereof. A bushing or packing 18 is secured within the opening 17 in any suitable manner, such as screw-threads, and said bushing is provided with an opening extending therethrough and through which passes a valve stem or rod 19.

A valve 20 is carried by one end of the rod or stem 19, and said valve is located within the coupling and is adapted to be seated against the adjacent end of the tube or pipe 12 for a purpose to be set forth.

Within the support 14 and at a suitable point is an arm or bracket 21, to which one end of a bar or lever 22 is pivotally connected. This rod or bar is preferably located below the coupling 16 and is pivotally connected intermediate its ends to the valve stem or rod 19 in any suitable manner, preferably by means of a pivot-pin 23. If desired, the extremity of the valve rod or stem 19 may be bifurcated to receive the lever or bar 22.

The free end of the lever or bar 22 projects through an opening 24 in the support, which is preferably located diametrically opposite the bracket 21, and said end projects beyond the support to form a handle.

Secured to the outer face of the support and over the opening 24 therein is a plate 25, which is provided with a slot 26, registering with the slot 24, and through this slot 26 the end of the lever or bar 22 passes. One wall of the slot is provided with a rack or teeth 27, which project into the slot 26.

The coupling 16 is also provided with lateral openings 28, preferably arranged diametrically opposite each other, and passing through suitable openings in the support 14 are pipes 29 30, which have one of their extremities secured within the openings 28 in any desired manner, preferably by means of screw-threads. The free ends of these pipes project beyond the support, and coupled to the end of the pipe 29 in any suitable manner, such as an ordinary coupling 30, is one end of a flexible pipe 31, to the free end of 20 which is a discharge-nozzle 32.

Extending from the opening 13 in the wall of the tank 10 is a pipe 33, the free end of which is connected to and communicates with the pipe by means of the coupling 34.

The free extremity of the pipe 30 is connected in any desired manner to any suitable source of supply or compressed-air tank.

In operation the tank is filled with sand or abrading material, the valve 20 having been first closed and secured against its seat by the engagement of the rod or lever 22 with the teeth 27. After filling the valve 20 may be adjusted to permit the desired amount of material to pass therethrough and secured in position by engaging the respective tooth 27 with the rod or lever 22. Air is then admitted into the pipe 30. Upon reaching the coupling 34 the air will be divided, a portion passing directly through the pipe 30, coupling 16, pipe 29, and nozzle 32, carrying with it the sand or abrading material which has been fed from the tank through the pipe 12, and into the coupling 16 and discharging the same with great force out of the nozzle 32 and upon the surface to be operated upon, the other portion of the air being directed into the tank for overcoming the upward pressure exerted by the air passing through the pipes 30 29 and for feeding the material thereto, 45 the inclination of the bottom of the tank serving to assist in feeding the abrading material.

It is to be understood that it is not desired to be limited to the exact details of construction or arrangement of the several parts, as

numerous changes may be made therein without departing from the spirit of the invention.

What I claim as new is

1. In a device of the class described, the combination of a closed tank, a support for the tank, an air-pipe, an outlet-pipe leading from the tank and communicating with the air-pipe, a valve adapted to close the end of the outlet-pipe, a lever pivoted to the support, a pivotal connection between the lever and valve, a rack on the support adapted to be engaged by the lever for securing the valve in position, and a connection leading from the pipe and opening into the tank.

2. In a device of the class described, the combination of a closed tank, a support for the tank, an air-pipe, provided with a nozzle on one end, an outlet-pipe depending from the bottom of the tank and communicating with the air-pipe, a valve adapted to close the end of the outlet-pipe, a lever pivoted by one end to the support, a pivotal connection between the lever and valve, a rack secured to the support and adapted to be engaged by the lever for holding the valve in position, and a connection leading from the air-pipe and communicating with the tank adjacent the bottom thereof.

3. In a device of the class described, the combination of a tank, a support upon which the tank is adapted to rest, an outlet-pipe depending from the bottom of the tank, a coupling secured to the free end of the pipe and provided with an opening in the bottom thereof opposite the pipe, a removable bushing within the opening, a valve-rod passing through the bushing, a valve on the rod adapted to be inserted in the coupling through the opening and to be seated against the end of the pipe and within the coupling, a lever pivoted to the support, a pivotal connection between the valve-stem and lever, an air-pipe comprising sections secured to the sides of the coupling to form a continuous passage therethrough, and a connection between the air-pipe and tank, said lever being adapted to adjust the position of the valve.

In testimony whereof I have signed my name to this specification, in the presence of two subscribing witnesses, on this 20th day of March, A. D. 1906.

E. A. ARCOUET.
